UNITED STATES PATENT OFFICE

WALTER E. CLIFFORD, OF BOSTON, AND JOHN E. WOODS, OF BROOKLINE, MASSACHUSETTS, ASSIGNORS TO CLIFFORD MANUFACTURING CO., OF BOSTON, MASSACHUSETTS, A CORPORATION OF DELAWARE

STEAM TRAP

Application filed November 7, 1931. Serial No. 573,589.

The present invention relates to steam traps, and more particularly to steam traps employing an expansible and contractible diaphragm containing a thermostatic fluid.

8 In this class of devices an expansible diaphragm is mounted within a trap body, and operates to close the outlet to the body when steam is contained therein, and to open to provide for egress for air and water of condensation.

10 The object of the present invention is to simplify and improve steam traps of this character in a manner to promote economy of production and insure uniformity of operation.

15 With this and other objects in view the various features of the invention consist in certain novel features of construction, combinations and arrangements of parts herein-
20 after described and claimed, the advantages of which will be obvious to those skilled in the art from the following description.

25 In the accompanying drawings illustrating the preferred form of the invention, Fig. 1 represents a section in elevation of the completed trap; and Fig. 2 is a similar section of the combined cap and bellows unit removed from the trap body.

30 The trap shown in the illustrated embodiment of the invention comprises a body portion 10 provided with an inlet connection 12 at one side and an outlet connection 14 at the bottom. The outlet connection is formed in the shape of a hexagonal nut internally
35 threaded at 16 to facilitate its connection to the return pipe of a steam system. The inlet connection 12 is threaded, and may be provided with a nut for connection with the radiator or steam consuming unit from a suitable form of union. The upper portion
40 of the trap body is closed by a cap 18, which is provided with a depending circumferential flange 20, threadedly engaged at 22 with corresponding threads formed on the body. The opposing faces 24 at the upper edge of
45 the trap body and the cap are machined to form plane surfaces capable of sealing the interior of the body against pressures employed.

50 It will be observed from the accompanying

drawings that the trap body is reasonably shallow and free from abrupt curves, which facilitates formation of the body complete as a forged unit. It is intended that both the body and the cap shall each be forged of brass or suitable material, with such parts machined as may be necessary for an accurate fit. In this connection it will be understood that either the body or cap or both might be cast without essentially affecting the device or its mode of operation, although from the standpoint of producing a leak-proof body and cap the forging is superior to the casting, which, in the absence of precautionary methods, may be porous.

55 The cap 18 is provided with a raised hexagonal portion 26 for attachment to the body, and interiorly is provided with a circular recess 28 of reduced diameter which fits the reduced neck portion 30 of a metallic bellows 32. The engagement of the reduced neck portion 30 with the recess 28 serves to center the bellows unit with respect to the cap, and the two are bonded in permanent relationship by a film of solder 33, extending outwardly from the circular recess between the contacting surfaces of the cap and the first bellows fold. The metallic bellows anchored at one end to the cap is integrally closed at its lower or free end 35, the end wall forming a portion of the cupped tube from which the bellows is constructed. This end wall, which is preferably thicker by a substantial amount than the thickness of the corrugated wall, is shaped to form a 60 tapered valve member 37, located centrally of the bellows unit. When the unit is thereafter assembled with the trap body, the tapered valve 37 is located centrally and above an outlet port 40 formed in the lower 65 portion of the trap body, and designed in cooperation with the valve 37 to automatically control the egress of air and water of condensation from the trap. The automatic operation of the bellows unit is secured as described in the previous patent of Clifford No. 1,816,142, by locating within the bellows unit water under a vacuum normally sufficient to maintain the unit in the contracted position shown at temperatures beneath the 70

boiling point. When the water within the bellows unit, on the other hand, is converted into steam by the presence of steam in the trap body and contact with the thin walls of 5 the unit, the vacuum is broken and the bellows unit, due to the equalization of pressure within and without, tends to assume a free length, causing the valve 37 to seat upon the edge of the port and close the outlet from 10 the trap until such time as the formation of water of condensation about the bellows condenses the steam therein, thus opening the valve.

With this construction it will be evident 15 that the metallic bellows permanently sealed to the cap form a complete thermostatic unit inserted in and removed from the trap body by insertion and removal of the cap without dismantling the body from the line. Furthermore, the thermostatic unit, due to the 20 fact that the bottom portion of the valve is integral with the bellows folds is free from soldered or bonded joints affording liability for leakage and presenting opportunity for 25 erosion from the action of the steam. The only bonded joint is the joint between the upper portion of the metallic bellows and the cap, completely covered by the opposing walls of the cap and bellows, and enclosed 30 and removed from the erosive action of the steam.

In producing this thermostatic unit, as described in our co-pending application filed 35 of even date herewith, the bellows unit is assembled with the cap, an opening being formed through the tip of the valve, and thereafter the unit is thermostatically filled and sealed by a solder button 42, located in 40 the valve tip and closing the relatively small opening therethrough.

This type of steam trap is economical to manufacture because the cap is made to complement the metallic bellows in producing a 45 complete thermostatic unit, and in addition the valve is formed from the material at the closed end of the unit rather than a separate element. Moreover, by the production of a 50 thermostatic unit comparatively shallow in depth, and seating this unit directly in the cap, a corresponding saving in the depth of 55 the trap body may be produced, which results in the saving in weight of material as compared with previous constructions of this character employing metallic bellows as the thermostatic element. A corresponding 60 unit of equivalent capacity employing a metallic diaphragm would require a much greater diameter to obtain the necessary action, with a consequently greater diameter 65 of body and increase in weight.

What is claimed is:

1. A steam trap comprising a trap body having an outlet port, an imperforate and one-piece forged cap detachably connected 65 with the body for sealing the upper portion

of the chamber therein, a metallic bellows having one end integrally closed except for the provision of a hermetically sealed opening therein, the bellows contacting about its open end directly with the interior seamless surface of the cap and bonded thereto to seal the space encompassed by the bellows and cap, a valve at the integral closed end of the bellows aligned with the outlet port when the cap is assembled with the body, and thermostatic fluid sealed within the expandable chamber formed by the cap and bellows to cause movement of the valve end of the bellows upon variation of temperature within the trap body. 80

2. A steam trap comprising a trap body having an outlet port, an imperforate and seamless cap detachably connected with the body for sealing the upper portion of the chamber therein and having a central recess 85 interiorly thereof and a comparatively flat surface surrounding the recess, a metallic bellows having one end integrally closed except for the provision of a hermetically sealed opening therein, the bellows having an opposite open end extending into the recess and positioned thereby and bonded directly to the interior surface of the cap in the area surrounding the recess to seal the space encompassed by the bellows and cap, a valve at 90 the integral closed end of the bellows aligned with the outlet port when the cap is assembled with the body, and thermostatic fluid sealed within the expandable chamber 95 formed by the cap and bellows to cause movement of the valve end of the bellows upon variation of temperature within the trap body. 100

3. A steam trap comprising a trap body having an outlet port, an imperforate and one-piece cap detachably connected with the 105 body for sealing the upper portion of the chamber therein, a metallic bellows having one end integrally closed and contacting at its opposite open end directly with the interior and seamless surface of the cap and bonded thereto to seal the space encompassed by the bellows and cap, the integral closed end of the bellows being formed to provide a 110 tapered valve extension aligned with the outlet port when the cap is assembled with the body and having an opening therethrough closed with solder or its equivalent to seal the space within the bellows, and thermostatic fluid sealed in the chamber formed by the 115 cap and bellows. 120

In testimony whereof we have signed our names to this specification.

WALTER B. CLIFFORD.
JOHN E. WOODS.
